UNITED STATES PATENT OFFICE

ROLAND B. RESPESS, OF WICKFORD, RHODE ISLAND

FAN DIFFUSER

Application filed September 27, 1924. Serial No. 740,263.

This invention relates to air circulating or ventilating systems and particularly to devices which may be associated with power driven fans for increasing their effectiveness in causing proper and thorough circulation of air within a given space.

Numerous devices are at present in use for distributing fresh air to rooms through duct systems and for stirring up the air to secure an artificial breeze. The duct systems may 10 distribute air to the different rooms or to various parts of the room but such systems fail in providing a proper means of circulating such air when delivered. As an aid in the distribution of the air electric fans are sometimes used to stir up the air in the room and some electric fans are equipped with oscillatory devices so that a breeze is intermittently delivered to different parts of the room, 15 but they fail however to cause a thorough circulation of the air within a given space and cause drafts that are dangerous and are commonly regarded as contributing to various illnesses. To obtain proper ventilation it is 20 necessary that the air be in continuous uniform circulation throughout all parts of the room and be kept in continuous motion to enable the oxygen to counteract the impurities ever-existent in the air.

Objects of this invention are to provide a 25 new and improved system of air circulation whereby the entire volume of air is kept in continuous movement within a given space; to provide means by which the air body is broken up so that the fresh air may mix easily 30 and intimately with the stagnant air so the new oxygen may counteract the impurities in the air; to provide a ventilating system that will provide a sufficient supply of fresh 35 air to every part of a room without draft; to provide a simple and inexpensive device for 40 association with power driven fans which increases air circulation to a marked degree without objectionable draft caused by ordinary devices of this character; and to design 45 such a device having the unique mode of operation and detail construction hereinafter fully described.

The invention relates to air circulation 50 within a given space, the air being forced into

such space through duct systems or open windows. In one phase the invention comprises a device which is adapted for association with power driven fans. Preferably the device is in the form of a hood or shield adapted to be substituted for or associated with the usual wire fan guard. This hood may be provided with a number of parallel openings which are horizontally disposed when the hood is in place, and adjacent to each opening a deflector may be arranged to deflect the air in a given direction. The size of the openings, and position and design of the deflectors are so chosen that the air is impelled in a vibratory manner and a slight compression takes place as the air is driven from the hood.

A genus of the invention is illustrated in the accompanying drawings in which

Fig. 1 is a side elevation of an electric fan of the usual type equipped with a hood embodying the present invention:

Fig. 2 is a perspective view; and

Fig. 3 is an enlarged diametrical vertical section of the hood.

In the illustrated embodiment of the invention the electric fan comprises a supporting base 1 on which is mounted for rotative adjustment an electric motor 2 having a shaft to which a fan comprising the blades 3 is attached, a control lever 4 being provided for regulating the speed of the motor. Electric fans of this character are usually provided with a wire guard for preventing accidental contact with the rapidly rotating blades, the guard being attached to radially extending 55 braces 5.

In accordance with the present invention the usual wire guard is removed and a shield or hood 6 replaces it, the hood being made of sheet metal or other suitable material and is attached by the braces 5. As shown the hood 6 is shaped more or less like a shallow pan, being preferably circular in form and comprising a front wall 6 and an integral, annular, rearward side wall or flange 8, the back 60 of the hood being open. The front wall 6 is provided, as by cutting or slitting the metal, with a plurality of parallel, closely spaced openings 9 which extend substantially the entire width of the hood. The metal above each

opening is bent rearward as indicated in Fig. 3 to form a plurality of parallel louvers or deflectors 10. It will be observed that the angularly bent deflectors 10 and the intermediate strips 7 together form a surface whose area is approximately twice as great as that of the openings 9.

When the motor 2 is started the blades 3 are rotated at a very great speed and the air is drawn freely through the open back into the hood where it takes up a rapid whirling forward motion sweeping against the inclined deflectors 10, thus being broken up into innumerable eddies, and is then driven into the elongate pockets formed by the strips 7 and deflectors 10 and thence outwardly through the openings. Owing to the fact that each of the spaced fan blades tends to produce an individual current or zone of pressure, there is a constant forward force pressure of these currents. Furthermore, because the size of the openings 9 is much less than the combined area of the strips 7 and deflectors 10, the whirling air is not impelled from the hood in a continuous current but is driven therefrom in vibrating waves in an upward direction. The area of the open back of the head through which the air enters is much greater than the combined area of the openings 9, and therefore the air is slightly compressed so that as it issues from the hood in an upward direction it expands. As the air is not driven from the hood in a direct and continuous current but is delivered in vibratory waves it expands quickly in every direction and a very great volume of air is kept in uniformly continuous motion without drafts.

The outstanding characteristic of this invention is its capability of producing a circulation of air in a given space so that the entire volume of air therein is affected and kept in continuous motion without the creation of drafts while the air thus circulated is found to be purified by the intimate contact with new live oxygen uniformly distributed within the space, with a pleasing and somewhat exhilarating sensation over the entire person exposed thereto and this effect is caused by the uniform absorption of pure live air into the body through the lungs and pores. The system or method in its essential details consists in thoroughly and energetically agitating the air in such manner that it takes up a whirling motion and impelling it in a given direction through nozzles or openings having deflectors in such a way as to create air impulses or waves. In this manner a curious vibratory effect is obtained which materially assists the air current in assimilating or mingling with the air in all parts of a given space, and as the air is broken up and slightly compressed before passing into the room its expansion exerts a certain effect which is unusually stimulating.

65 I claim:

A cover for the blades of a fan comprising a hood of thin sheet material having a front wall provided with a plurality of closely spaced parallel openings, a closed side wall surrounding the blades of the fan, and a plurality of deflectors carried by said front wall, 70 each deflector extending inwardly toward the blades of the fan from one edge of an opening. Signed by me at Boston, Mass., this 25th day of September, 1924.
